Primary Examiner — Adir Aronovich(74) *Attorney, Agent, or Firm* — Wolf, Greenfield & Sacks, P.C.; Randy J. Pritzker(57) **CLAIM**

The ornamental design for a digital camera, as shown and described.

DESCRIPTIONFIG. 1 is a front perspective view of a first embodiment of a digital camera showing our new design;
FIG. 2 is a front elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a front perspective view of a second embodiment of a digital camera showing our new design;
FIG. 8 is a front elevational view thereof;
FIG. 9 is a top plan view thereof;
FIG. 10 is a bottom plan view thereof;
FIG. 11 is a right side elevational view thereof; and,
FIG. 12 is a left side elevational view thereof.
The features shown in broken lines in the drawings depict environmental subject matter only and form no part of the claimed design. The dot-dashed lines denote the boundary of the claim, and form no part of the claimed design.**1 Claim, 12 Drawing Sheets****FIG. 1**
